RECEIVING DEVICE FOR REMOTE-CONTROL
INSTALLATIONSHans Tobler, Zurich, Switzerland, assignor to
Landis & Gyr, A. G., a body corporate of SwitzerlandApplication February 5, 1948, Serial No. 6,543
In Switzerland December 10, 1946Section 1, Public Law 690, August 8, 1946
Patent expires December 10, 1966

10 Claims. (Cl. 177—353)

1

The invention relates to a novel and improved receiving device for remote control installations, more particularly for central remote control systems operating on the synchronous selector principle, with a resonant receiving circuit tuned to an audio-frequency.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

The single figure of the drawing schematically illustrates a typical and preferred form of a receiving device embodying the present invention.

In one receiving device of this type heretofore known, the circuit of a synchronous motor is closed after the reception of a starting impulse by a receiving relay, and causes a rotating contact arm to slide along a circular contact path, switching itself off automatically on the completion of a complete rotation of the contact arm. While the rotary contact arm is turning, control impulses are sent out, which are so timed that they only become effective in the receiver when the rotating contact arm is over the corresponding path contacts. Trigger relays are connected to the latter and may be switched on and off by the received control impulses. This known device has the disadvantage that a special trigger relay is required for every double control, and in the case of a large number of double controls, the device is unduly large.

In another known receiving device the rotating contact arm is replaced by a switch arm, which is capable of actuating pairs of contactor switches, in such a manner that the contactors are, for instance, switched off when the switch lever rotates in an upper plane and are switched on when it rotates in a lower plane. If, after the starting impulse, no control impulses are received, the switch arm completes its rotation in the upper plane only, and disconnects all the contactors if they are not already disconnected. If, on the other hand, a control impulse is received, the switch arm drops temporarily into

2

the lower plane and switches on the contactor in question. This latter device possesses the disadvantage that a separate relay must be provided for the axial motion of the shaft bearing the switch arm.

Furthermore, receiving devices are known where a shaft carrying a switch arm and driven by a synchronous motor periodically transmits impulses during a rotation, the position of a catch being controlled by a receiver resonating relay, the impulses being used for actuating switching devices by means of the switch arm. However, only a relatively small portion of the complete rotation of the shaft is available for actuating the switches, since in a rotation of this kind some fifty controls are to be transmitted in all. Receiving devices of the latter type have the disadvantage that only relatively small switches can be actuated by the usual dimensions of the synchronous motor.

Receiving devices have therefore been devised in which part of the rotation of the shaft carrying the switch arm is used for winding an energy storage spring. The impulses cause this spring to be released, while the actual switching operation is performed by the energy storage spring. By this means it is possible to actuate heavy switches. A disadvantage of these well known devices is that part of the rotation of the control shaft is wasted for transmitting controls, and that the force available in practice for operating the switches is always relatively small.

The receiving unit according to the invention avoids these disadvantages in that at least one energy storage spring, which is released for actuating each switching device, is stressed during the complete rotation of a control shaft every time the receiver is put into operation.

The present invention has for its object the provision of a novel and improved receiving unit which is simple, compact, positive in operation, of relatively low cost construction and avoids defects of the prior constructions. A further object is the provision of such a device which is capable of actuating relatively heavy single or multiple-pole switches in a positive manner and with a relatively small amount of controlling power and a minimum of complexity in the receiving apparatus.

It will be understood that the foregoing general description and the following detailed description as well are exemplary and explanatory of the invention but are not restrictive thereof.

Referring now in detail to the illustrative embodiment of the invention as shown in the draw-

ing, *a* and *b* denote two conductors of a low voltage A. C. network (such as 110 volts, 60 cycle) onto which audio-frequency control voltages can be superposed. Between the conductors *a*, *b* there is connected in series a resonant circuit, consisting of a capacitance *1* and an inductance, such as the coil winding *2*. The latter is formed as a resonant relay winding and together with the capacitance *1* is tuned to the transmitting frequency. In addition to conventional components not shown in the drawing, such as the iron core, bearings etc., the resonant relay has a rotatable armature *3*, which may turn in the direction of the arrow when the resonant relay is excited. On the spindle *4* of the rotating armature *3* are mounted two cams *5* and *6*, the former serving to operate a switch or contactor *7*, *8*, and the latter adapted to raise a release lever *9* to rotate about its axis *10*, *11*. The contactor *7*, *8* is connected in series with a synchronous motor *12* across the mains *a*, *b*. The motor drives a control shaft *15* in an anti-clockwise direction through a pinion *13* and gear-wheel *14*, and cam shaft *19* through gear-wheels *16*, *17*, *18*. On the control shaft *15* there are provided an "on" control wheel *20*, an "off" control wheel *21* and a cam wheel *22* with a notch *23* for actuating the contactor *7*, *8*. Control wheels *20*, *21* are carried on the control shaft *15* so that they can easily be angularly moved for adjustment and fixed in the desired position. Control wheels *20*, *21* moreover each have a notch, *24* and *25* respectively, into which projections *26* and *27* on the two control levers can drop. The control discs are preferably indexed so they can be set to a fixed mark. The control levers are formed as leaf springs *30*, *31* mounted at one end, and the projections *26*, *27* have on the left-hand side upwardly directed arms *28*, *29*, extending into the path of movement of the release lever *9*. Leaf springs *30* and *31* also each have a projection, *32*, *33* respectively, directed downwards, coacting with a four-armed "on" cam *34* and with a four-armed "off" cam *35* respectively to form an escapement. These two cams are arranged at a definite angle relatively to one another, and for instance, when the upper arm of the cam *34* has been released by the projection *32*, the upper arm of the cam *35* is still held by the projection *33*. A switch cam *36* is interposed between the cams *34*, *35*, and is likewise provided with four arms to work in conjunction with the lower contact spring extended to the right of a contactor *37*. The three cams *34* to *36* are fixed in respect of each other, either being made integral or rigidly connected together in the relative positions shown. Cam unit *34*, *35*, *36* is loosely supported on the shaft *19*. The transmission of the rotary motion of the shaft *19* to the cam unit takes place through an energy storing spring *38*. At one side, the rear end of the latter bears against a sleeve rigidly connected to the gear-wheel *18*, and extending so far as the rear side of the cam *34*; in addition to transmitting the rotary motion by using the friction between the sleeve and the energy storing spring, this also serves to maintain the correct distance between the gear wheel *18* and the cam unit, since it lies against the hub of the cam unit, which is formed with a cylindrical cavity in the body of the cam, which serves for the reception of the energy storing spring. In the interior of the body of the hub, the energy storing spring presses against the outer cylindrical wall of the cylindrical cavity.

In front the axial position of the cam unit can be fixed by a collar *39* fixed on the shaft *19*.

At the end of the starting impulse, the bent end of the spring contact member *8* rides on the surface of the cam disc *22* and cannot drop into the notch *23* until cam *22* has made a full revolution. Consequently contacts *7* and *8* are maintained closed for a predetermined period after the impulse has ceased. A complete rotation of the cam disc *22* is required to break the circuit at the contacts *7* and *8*, and a short starting impulse will always positively start a complete rotation of the control shaft *15*. At the same time that cam *5* closes contacts *7* and *8*, cam *6* lifts the release lever *9*, but this lifting has no effect on the levers *30* and *31* as these levers are held in place by the projections *26* and *27* which press against the surface of the control wheels *20*, *21*. Synchronous operation of the transmitter and receiver insure that the control impulses for actuating the contactor *37* are sent out during the rotation of the control shaft *15*, and at times when the corresponding notches *24* and *25* in the control wheels *20* and *21* are exactly opposite the projections *26* and *27* of the control levers *30*, *31*. If no control impulses occur during the revolution of the shaft *15* projections *26* and *27* tend to drop into the notches *24* and *25* of the control wheels *20* and *21*, but are prevented from doing so to any considerable extent by means of the upwardly extending arms *28* and *29* which rest against the release lever *9* and are thereby blocked against further movement. On the other hand if a control impulse reaching the receiver and actuating the relay armature *3* is properly timed, cam *6* lifts the release lever *9* at the moment when notch *25* is opposite the projection *21* or notch *24* is opposite the projection *26*, thereby allowing the lever *30* or *31* to be actuated. The raising of leaf spring lever *31* when an impulse actuating the relay *2*, *3* causes the release lever *9* to be lifted when notch *25* is opposite the projection *27* lifts detent *33* far enough to clear the upper arm of cam *35* thereby freeing cam *35* and the cams *34* and *36* fixed to it. When cam *35* is freed, the loaded energy storing spring *38* drives the cam unit in a counter-clockwise direction until one of the arms of cam *34* strikes against stop *32* depending from the leaf spring lever *30* thereby resulting in almost a 90° revolution of the cams *34*, *35* and *36*. During this rotation of the switch cam *36*, its arm engages the forwardly extending end of the lower contact spring of the contactor *37* causing the contactor to open. When the contactor *37* is to be closed again, the resonant relay *2*, *3* in the receiver must be again excited and this excitation must occur when the notch *24* of the control disc *20* is in a position to receive the projection *26* on the spring lever *30*. At this time the excitation of the relay causes the release lever *9* to be lifted so that projection *26* can drop into the notch *24*, thereby causing the stop *32* to be lifted out of the path of the arm of cam *34* which it is holding against rotation. This action frees the cam unit to turn until an arm of cam *35* engages the stop *33* thereby stopping the cam unit in the position shown and with the contactor *37* in closed position as the arm of switch cam *36* has slid off the front end of the contact spring of contactor *37* to close the contactor circuit.

In closing the contactor the cam unit carries out only a small rotational movement corresponding

to the angle of displacement between the adjacent arms of cams 34 and 35, while the cam unit carries out a much greater rotational movement to open contactor 37 and more energy is available for the opening movement than for the closing movement so as to overcome the strength of the spring member of contactor 37.

Energy storing spring 38 is energized or loaded each actuation until it begins to slip by rotation of the shaft 19 which is driven from the synchronous motor 12 through gearing 13, 14, 16, 17 and 18. As soon as one of the arms of cams 34 or 35 strikes the corresponding projection 32 or 33, the energy storing spring 38 is partially loaded, and is increasingly loaded by the continued rotation of the shaft 19. Thus practically the complete time corresponding to a full revolution of the control shaft 15 is available for the loading of the energy storing spring 38 so that a relatively small synchronous motor 12 may load a very powerful storage spring 38 and provide sufficient force to actuate relatively heavy single or multiple pole contactors.

The apparatus shown in the drawings may be extended to actuate a plurality of contactor units each of which would include a separate cam unit 34, 35, 36, a separate energy storage spring 38, control levers 30 and 31 and control wheels 20 and 21, all subject to the same resonant relay 2, 3 and driven from the same synchronous motor 12 under control of the cam disc 22.

The invention in its broader aspects is not limited to the specific mechanisms shown and described but departures may be made therefrom within the scope of the accompanying claims without departing from the principles of the invention and without sacrificing its chief advantages.

What is claimed is:

1. A receiving device for remote control installations including in combination a relay, a synchronous motor, control discs driven by the motor and having notches on their peripheries, a switch, a plurality of control levers abutting the peripheries of said control discs and normally restrained from following said discs at the notches of the discs, cam means normally restrained by said control levers and operative when said levers follow the notches on said discs to open or close said switch, and detent means actuated by the relay for preventing said levers from following said disc notches except when the relay is actuated.

2. A receiving device as claimed in claim 1, in which a spring wound by the synchronous motor rotates said cam means upon their release by the control levers to open or close said switch.

3. A receiving device as claimed in claim 2 in which the relay controls a second switch permitting the synchronous motor to be energized for a complete cycle of operation.

4. A receiving device for remote control installation including in combination a relay, a synchronous motor, a pair of control discs geared to the motor and having notches on their pe-

ripheries, a pair of control levers selectively movable into a notch in the corresponding control disc, an escapement controlling a switch and controlled by said control levers and discs, detent means actuated by said relay preventing movement of either control lever into a control disc notch except on simultaneous actuation of said relay, and a switch actuated by said relay and controlling said motor for energizing said motor for a full cycle of operation.

5. A receiving device as claimed in claim 4 in which the motor winds a spring which energizes the actuation of the escapement controlled switch.

15 6. A receiving device as claimed in claim 4 in which the control discs are adjustable to vary the angular relation of their control notches.

7. A receiving device as claimed in claim 6 in which one control disc controls the closing and 20 another controls the opening of the escapement controlled switch.

8. A receiving device as claimed in claim 7 in which the motor winds a spring to energize the opening and closing of the escapement controlled switch.

25 9. A receiving device as claimed in claim 8 in which a cam disc driven by the motor maintains the motor switch closed until the cycle of operation has been completed.

30 10. A receiving device for remote control installations including in combination a relay, a pair of cams controlled by the relay, a motor, a switch controlled by one cam for supplying power to the motor, a shaft driven by the motor and driving a control disc for keeping the switch closed until the shaft has completed one revolution,

35 36 a second switch, an escapement controlling said switch and including two members, one for releasing the escapement to open, and the other for closing said second switch, a spring wound by said motor for actuating said second switch under control of the escapement, a pair of rotary control discs co-operating with said members and driven in timed relation by said motor 40 whereby said escapement members are selectively controlled and released only at a predetermined point in the rotation of said control discs, and means actuated by the other of the first pair of cams for preventing release of the escapement except when the relay is actuated in proper timed relation with the release of a selected escapement member and the spring is wound on such actuation of the relay.
